CLAIM

The ornamental design for a pet chew toy, as shown and described.

DESCRIPTION

FIG. 1 is an upper right perspective view of a pet chew toy showing our new design.

FIG. 2 is a bottom right perspective view thereof.

FIG. 3 is a front elevation view of thereof.

FIG. 4 is a top plan view thereof.

FIG. 5 is a rear elevation view thereof.

FIG. 6 is a bottom plan view thereof.

FIG. 7 is a left side elevation view thereof; and,

FIG. 8 is a right side elevation view thereof.

The dot-dot-dashed broken lines in the drawings illustrate portions of the pet chew toy that form no part of the claimed design.

1 Claim, 8 Drawing Sheets
